UNITED STATES PATENT OFFICE.

JAMES H. TOPP AND EDWIN VOSBURGH, OF JOHNSTOWN, NEW YORK.

LEATHER-WORKING MACHINE.

SPECIFICATION forming part of Letters Patent No. 644,479, dated February 27, 1900.

Application filed November 21, 1899. Serial No. 737,795. (No model.)

To all whom it may concern:

Be it known that we, JAMES H. TOPP and EDWIN VOSBURGH, citizens of the United States, residing at Johnstown, in the county of Fulton 5 and State of New York, have invented certain new and useful Improvements in Leather-Working Machines; and we do hereby declare the following to be a full, clear, and exact description of the invention, such as will enable 10 others skilled in the art to which it appertains to make and use the same.

This invention relates to machinery for working skins, hides, leather, and kindred material required to be softened or rendered 15 pliable or flexible by manipulation.

The machine is chiefly designed for staking or breaking leather, although its construction is such as to admit of a variety of operations in the treatment of hides, skins, and leather. 20 For a full description of the invention and the merits thereof and also to acquire a knowledge of the details of construction of the means for effecting the result, reference is to be had to the following description and 25 the drawings hereto attached.

While the essential and characteristic features of the invention are necessarily susceptible of modification, still the preferred embodiment of the invention is illustrated in the 30 accompanying drawings, in which—

Figure 1 is a perspective view of a machine constructed in accordance with the invention. Fig. 2 is a side elevation. Fig. 3 is a rear view. Fig. 4 is a central longitudinal section. Fig. 5 is a detail view in elevation of the cam for the adjustable end of the flexible apron, showing the relation of the actuating-springs. Fig. 6 is a detail perspective view of the outer end of an arm carrying a blade. 35 Fig. 7 is a view of the parts shown in Fig. 6, illustrating the means for adjustably connecting the blade with the arm. Fig. 8 is an end perspective view of the blade.

Corresponding and like parts are referred 40 to in the following description and indicated in all the views of the drawings by the same reference characters.

The base for the superstructure comprises 45 sills 1 and cross-beams 2. Posts 3 rise from the sills at an intermediate point and are stayed by the braces 4 and cross-timber 5. A

shaft 6 is journaled in bearings provided at the upper ends of the posts 3 and is adapted to be driven from a suitable source of power by means of a belt (not shown) passing around a 55 band-pulley 7, applied to the shaft 6, the latter carrying the staking mechanism. An upright 8 rises from the front cross-beam 2 at about a middle point, and an upright 9 is located at a corner of the base. A cross-bar 10 60 connects the upper ends of the uprights and is about equal in length to the front timber 2 and disposed parallel therewith, a vertical bar 11 connecting the terminal of the bar 10 with the adjacent corner of the base and having teeth 65 12 at its upper end. Concaves 13 have their ends secured, respectively, to the cross-bar 10 and cross-timber 5 and are transversely spaced apart at their inner longitudinal edges about five or six inches and are stiffened at 70 their edges by means of strips 14, having their upper edges made concave to come flush with the supporting-surfaces of the beds 13. The concaves 13 form beds or supports for the material to be treated, and their upper 75 surfaces are practically concentric with the shaft 6. The space between the concaves or beds 13 is occupied by an apron 15, of flexible material, preferably stout leather, one end being attached to the upper end of the upright 8 and the other end to a cam 16, mounted for movement upon a shaft 17. This apron 80 15 sags between its ends and approximates the concavity of the beds 13 and supports the material against the action of the staking- 85 blades.

The hide, skin, leather, or like material to be treated is placed upon the beds 13 and the apron 15 and is subjected to the action of the staking mechanism. The material is shifted 90 to bring every portion in position to be operated upon by the staking mechanism, and in order to allow for variation in thickness the apron is adapted for adjustment to vary its sag. This is effected by turning the cam 16 about 95 its axial support, a downward movement of the rear end of the cam serving to tighten the apron and an upward movement of said end serving to permit the apron to sag to a greater extent, as will be readily understood. A foot- 100 lever 18, pivotally connected at its rear end with the rear cross-timber 2, extends longi-

tudinally of the frame and is connected with the rear end of the cam 16 by means of a stout contractile spring 19, and a downward movement of the free end of said lever 18 tends to 5 open the spring 19 and to depress the rear end of the cam 16, whereby sag in the apron 15 is taken up and the staking mechanism caused to act with greater force upon the material in position to be treated. A return- 10 spring 20 connects the front or opposite end of the cam 16 with the cross-timber 5, its purpose being to depress the front end of the cam when the front end of the foot-lever 18 is elevated. The free end of the foot-lever 15 18 is expanded to provide a rest for the foot and is connected by means of a rod 21 with a transversely-disposed hand-lever 22, pivoted at one end to the upright 9 and having its opposite end formed with a cog or lip 23 to engage with any one of the series of teeth 12 of the rod 11, so as to hold the foot-lever 18 in the adjusted position. A keeper 24 is applied to the front side of the upright 8 and receives the lever 22 and prevents casual displacement 25 of the cog 23 from the engaging tooth 12. The rod 21 is adjustably connected with the foot-lever 18 to suit the convenience of the operator. A spring 25 connects the free end of the foot-lever 18 with the upper portion of the 30 upright 8 and is provided to return the said lever to a normal position when liberated by disengaging the lip 23 from the teeth 12.

Oppositely-disposed arms 26 project radially from the shaft 6, and their outer ends 35 are expanded and terminate in concavo-convex heads 27, to which are fitted blades 28 of corresponding shape, the outer or active ends of said blades being of convex outline to prevent injurious contact therewith of the material being treated. The blades 28 are formed, preferably, of blanks of sheet-steel transversely curved between their longitudinal edges and formed with spaced longitudinal slots 29, which receive the bolts or fastenings 40 30, by means of which said blades are adjustably connected with the heads 27, so as to allow for wear. The heads 27 of the arms 26 are outwardly flared to provide an extended bearing for the blades 28 and are formed with 45 50 openings in relation with the slots 29, so as to receive the fastenings 30.

In the practical operation of the machine the shaft 6 is rotated by power applied to the band-pulley 7 in any convenient manner, and 55 the hide or material to be treated is placed upon the beds 13 and apron 15 and is moved so as to bring every portion in position to be acted upon by the blades 28. The effective distance between the apron 15 and the extremities of the blades 28 can be adjusted by 60 moving the cam 16 either by pressing downward upon the outer end of the lever 18 with the foot or by moving the outer end of the lever 22 downward by a combined action of the 65 two levers. When the position of the apron is attained, it is fixed by bringing the tooth

or lip 23 of the lever 22 into engagement with the teeth 12. The apron 15 being flexible yields to a certain extent, whereby injury to the material under treatment is obviated, and 70 the same result is attained by the yielding connection with the cam 16 and the lever 18, said connection or spring 19 yielding to permit the apron to give in the event of the thick portion of the material being engaged by the 75 blades or staking mechanism, thereby obviating injury to the machine, as well as to the material operated upon. It is to be understood that the apron-adjusting mechanism may be located at either end, or for convenience it is disposed in the manner set forth. 80

Having thus described the invention, what is claimed as new is—

1. In machinery for working leather and the like, and in combination with a staking mechanism, an apron, a tension device having one end of the apron connected therewith, and mounted for tilting movement, an operating-lever, a spring positively connected at its ends with, respectively, the tension device 85 and the operating-lever, and means for holding the lever in an adjusted position to vary the tension of the said connecting-spring and apron, substantially as set forth.

2. In leather-working machinery of the 95 character described and in combination with a staking mechanism, a tension-regulating device at one end of the apron and connected therewith and mounted so as to turn about an axial support, an operating-lever, a spring 100 connecting the tension device with the operating-lever, and a second spring disposed for returning the tension device to a normal position when the operating-lever is released, substantially as specified.

3. In leather-working machinery and in combination with a staking mechanism, an apron, a pivotally-mounted tension device 110 disposed to vary the relation of the apron with reference to the staking mechanism, an operating-lever, a spring connecting said lever with the tension device, a hand-lever operatively connected with the first-mentioned lever, and a spring for returning the parts to a normal position, substantially as set forth. 115

4. In leather-working machinery, staking mechanism including an arm having its outer end flattened, outwardly flared and transversely curved, a blade transversely curved and having its edge made rounding or convex and formed with parallel slots, and fastenings adjustably connecting the blade with the outer end of the aforesaid arm, substantially as described.

5. A machine of the character described, 125 comprising a base, uprights forming the base, staking mechanism applied to the upper ends of the uprights, a cross-timber connecting the uprights, concave beds transversely spaced and having their lower ends attached to the cross-timber, an apron located in the space formed between said beds, a pivotally-mount-

ed cam having the lower end of the apron attached thereto, a foot-lever, a spring connecting one end of the cam with the foot-lever, a second spring connecting the opposite end of the cam with said cross-timber, a hand-lever connected with the foot-lever, and a spring for returning the parts to a normal position, substantially as set forth.

In testimony whereof we affix our signatures in presence of two witnesses.

JAMES H. TOPP. [L. S.]
EDWIN VOSBURGH. [L. S.]
